DISPENSING DEVICE

Paul E. Moes, West Orange, and Michael E. McGowan, Bloomfield, N. J., assignors to Westinghouse Electric & Manufacturing Company, East Pittsburgh, Pa., a corporation of Pennsylvania

Application June 20, 1941, Serial No. 398,936

8 Claims. (Cl. 221—104)

This invention relates to a dispensing device, and more particularly to gas charging apparatus which, in the present disclosure, is specifically a mercury doser for lamps utilizing mercury vapor.

Various devices and methods have been employed heretofore in the manufacture of lamps and the like, wherein is required a small quantity of mercury or other fluid material, for introducing the charging material into the envelope. Several obstacles not heretofore fully overcome are encountered in connection with introduction of the fluid. Uniformity of dosage under varying conditions of fluid level, vacuum degree, speed of operation and similar factors, should be maintained. Avoidance of contamination of the fluid and feeding only clean fluid material are essential. Yet the best known doser heretofore employed presents a large open passage from the exhaust connection on the lamp to the area above the reservoir of fluid, enabling glass or other contamination from a broken lamp or other source to find refuge in the reservoir. That same doser likewise has the pick-up means so situated and operated that the contamination on the surface of the fluid can be and is picked up and fed into lamps being dosed, to their detriment. Frequent cleaning of such dosers is accordingly necessary with attendant loss of much of the dosing material.

An object of the present invention is to accurately measure and deliver to the lamp the desired dosage of fluid material in precise amount during evacuation of the lamp.

Another object of the present invention is to feed only clean, uncontaminated fluid dosing material.

A further object of the present invention is to avoid varying head of dosing material in the reservoir or varying degree of evacuation adversely influencing the supply of dosing material fed to each lamp.

A still further object of the present invention is to avoid frequent cleaning of the reservoir and to avoid waste and loss of the dosing material due to frequent cleaning.

Yet another object of the invention is to avoid introduction of pressure variation in the doser or lamp due to reciprocation of mechanism therein;

Still further objects of the invention will appear to those skilled in the art as the description progresses, both by direct statement thereof and by implication from the context.

In the accompanying drawing, wherein like

numerals of reference indicate similar parts throughout the several views, and wherein a preferred physical embodiment of the invention is disclosed by way of example:

5 Figure 1 is a vertical sectional view of the selected and preferred fluid charging apparatus mounted in operative position upon the exhaust machine, a portion only of which is indicated, and in charging relationship to a lamp likewise shown only in part;

10 Figure 2 is a cross-sectional view of the charging apparatus at the valve level through the reservoir on line II—II of Figure 1;

15 Figures 3 and 4 are vertical sectional views through the valve and delivery tube substantially on line III—III of Fig. 2, showing respectively the charge-receiving and charge-delivering positions of the valve gate;

20 Figures 5 and 6 are vertical sectional views on line V—V of Figures 1 and 2 showing the valve gate controlling cam in the positions which obtain placement of the valve gate in the charge-receiving and charge-delivering positions of Figures 3 and 4 respectively; and

25 Figure 7 is a plan of the valve gate.

In the specific embodiment of the invention illustrated in said drawing, the reference numeral 10 designates the revolving conveyor or other part of the exhaust machine on which the fluid charging apparatus of the present invention is mounted and with which said apparatus is utilized. Inasmuch as apparatus for exhausting and fluid charging lamp bulbs is well known, in its general aspects, in the art, this part of the mechanism is only fragmentarily illustrated in order to show relationship therewith of the improvement embodying the present invention. It may be stated, however, that the conveyor 10 provides a pinch jaw housing 11 in which is mounted a rubber tube connection 12 flanged at its upper end and retained by an encompassing fitting 13 screwed into the top of the jaw housing. The lower end of said rubber tube 12 is shown opening downwardly and receives the exhaust tube 14 temporarily formed as part of the lamp 15 being manufactured. Above and in continuation of the passage through the rubber tube 12, said fitting 13 provides a vertical central passage 16 the upper end of which is flared and threaded and receives a threaded bottom nipple 17 on our improved fluid charging apparatus, which is thereby mounted in place. From one side of the fitting 13, in communication with the said passage 16 therein, is a lateral connection 18 to

30 35 40 45 50 55

the exhaust pump (not shown) of the exhaust-ing machine.

The fluid charging apparatus of the present invention preferably comprises a cylindrical body portion 19, with said nipple 17 projecting axially from the bottom thereof. The interior of this cylindrical body portion comprises a chamber or reservoir 20 which accommodates certain hereinafter described mechanism and a supply or deep pool of the charging fluid 21, such as mercury. The upper end of the body portion is suitably faced to receive a gasket 22 upon which seats the lower flange 23 of a stack-like casing 24, the upper end 25 of which is closed. A screw cap 26 overlies said flange 23 with anti-friction means 27 interposed, the threaded skirt portion of the cap screwing onto the outside upper margin of the body portion 19. The structure thus described provides for a top closure for the reservoir which may be readily removed for refilling the reservoir and replaced tightly with ease, and which is vacuum tight.

Centrally upright at the bottom of the reservoir is situated a delivery tube 28 having its passage in communication with the passage 16 in the fitting. The specific construction shown provides an integral peripheral rib 29 on the delivery tube seated in a corresponding socket in the bottom of the reservoir, and with the tube extending both up and down from said rib. The lower ex-tending portion of said tube 28 protrudes from the bottom of nipple 17, is threaded and receives a nut 30 which rigidly holds the tube and tightly seats said rib 29 thereof, with a vacuum-tight seal. However, at the outside of the tube below said rib is provided a bleeder channel 31 which extends, as well, through the threaded portion of the nut 30. An intercepting channel 32 com-municates with bleeder channel 31, being suitably formed in the body portion 19 and opening into the reservoir 20 near the top thereof at 32' so as to be always above the pool level of the charg-ing fluid. Equalization of the negative pressure due to exhausting from the exhaust machine pump is accordingly effected, and yet the bleeder channel operates as a preventative to passage of glass or other extraneous matter passing to the reservoir.

An essential feature of the present invention resides in the valve structure near the bottom and within the reservoir, for measuring a globule of the charging fluid and passing it to the delivery tube 28 and thence to the lamp. This valve 33 preferably comprises a pair of horizontally dis-posed parallel plates 34, 35 integrally formed with an intervening spine portion 36 next one end thereof. The lower one, 35, of said plates is apertured at its middle part and mounted, with a pressed fit or otherwise permanently on the upper end of delivery tube 28 transverse thereto with the passage of said tube opening thru the upper side of the said lower plate 35 substantially flush therewith.

Between plates 34, 35 is provided a valve gate 37 also in a horizontal position and having a thickness substantially equal to the spacing be-tween said plates. This gate is pivotally mounted to swing in its own plane and in one extreme position of its amplitude of swing provides a measuring orifice 38 which will register with the upper opening of said delivery tube 28. The upper plate, however, above said delivery tube and orifice when thus situated and as shown in Figures 1 and 3, is solid, thereby preventing ingress of fluid to the orifice, but egress of the globule of fluid

in the orifice is permitted by gravitation into said tube. At its other extreme position of amplitude of swing, the said gate 37 situates said orifice 38 in registration with aligned openings 36, 39 in the upper and lower plates 34, 35 as shown in Figures 2 and 4. These openings 36, 39 are in direct communication with the charging fluid which respectively overlies and underlies said openings and, accordingly, freely enters said openings at top and bottom of the valve struc-ture. Thus, when gate orifice 38 registers with aligned openings 36, 39 above and below it, no air pocket results and the orifice is entirely filled with the charging fluid. As the gate swings again, the charging material is virtually sheared by the top and bottom edges of the orifice and a precisely measured globule of the material is carried within the orifice.

Preferably said gate orifice 38 is reamed to have a downwardly outward flare, by virtue of which the globule of material will be influenced by its inherent surface tension, to form as a globule and readily drop into the delivery tube 28 upon registration of the gate orifice with said tube. It has also been found advantageous to avoid smoothing or polishing the orifice or other parts in engagement with the mercury. Surface tension within the mercury has been found to exceed its tendency toward amalgamation and capillary adhesion to the orifice and other walls when said walls have a machined finish as dis-tinguished from a smoothed or polished finish. Furthermore, reaming said orifice enables the same to be brought to a precise capacity for the desired quantity of the charging material, and, in combination with the shearing effect above explained, absolute measurement is obtained each time the gate is swung.

The mechanism for swinging the gate includes provision of a solenoid core 40 slideable vertically and longitudinally within the stack-like casing 24. This core preferably has grooves 41 longitudinally thereof for enabling vacuum pressure to equalize at both ends and avoid either hinderance to operation of the plunger-like core or creation of varying pressure in the reservoir due to operation of the core in effecting its stroke in either direction.

A solenoid coil 42 is situated in or brought into encircling relation to the casing 24 and core 40 at the period of cycle of operation on the lamp when it is desired to admit the charging dose. As will be understood, the circuit connec-tions 43 to the solenoid are under suitable timed energizing power supply to actuate the solenoid at the proper moment.

The lower end of core 40 projects below casing flange 23 into the top part of reservoir 29 and is provided with an axially depending threaded stud 44. A yoke 45 is carried at a midpart of itself by threaded engagement with said stud and retained in adjusted position by lock nut 46. Said yoke, being transverse to the stud, is horizontally disposed, and has a shape such that fluid may readily pass between said yoke and the side walls of the reservoir. Next opposite end portions of the yoke are secured with respect thereto two parallel vertical depending rods 47, 47, the axes of which are parallel to and equidistant on oppo-site sides of the extended axis of the solenoid core. One of these rods passes slidably through a hole for the purpose in the spine portion 36 of the valve 33 (see Figures 1 and 2), whereas the other rod passes slidably through plates 34, 35 and

gate 37 and constitutes the hinge or pivot for said gate.

Next the spine portion 36 of the valve, said plates 34, 35 have slots 48, 49 through which freely passes a vertically disposed bar-like cam member 49 parallel to and situated between the rods 47, 47 with its flat sides facing said rods. This bar-like cam member 49 is off-set from the axis of the solenoid core 40 on the far side from the rod 47 which acts as a hinge for the gate 37. The edge of the gate toward the bar-like cam is arcuate, with a center of curvature coincident with the hinging of the gate, and from a mid-part of this arcuate edge projects horizontally a pin 50. The bar cam has a diagonal or upwardly sloping cam slot 51 therein which receives pin 50 therethrough. The position and inclination of the slot and relation of the pin are arranged to effect an oscillation of the pin and gate resultant upon vertical reciprocation of the bar cam. Said bar cam is secured at its upper end, as by welding, to the underside of yoke 45 which, accordingly, obtains a horizontal oscillation of the gate by a vertical reciprocation of the solenoid core.

The various parts are so constructed and related that the solenoid core 41 tends to assume its downward position under influence of gravity and the lower ends of rods 47, 47 then engage the bottom wall of the reservoir as a limitation to downward movement, such position of parts being substantially existent in Figure 1. At such time, pin 50 is in the upper end of cam slot 51 as shown in Figure 5, and orifice 38 of the gate 37 is in charge receiving position in registration with plate openings 39, 39 as shown in Figures 2 and 4. When solenoid 42 is energized, core 40 is lifted, its upper extremity engaging upper end wall 25 of the stack-line casing 24 as a stop. By virtue of the inclination of cam slot 51, pin 50 is swung laterally thereby moving orifice 38 out of registration with openings 39, 39 and into registration with the charge delivery tube 28, carrying a precisely measured globule of the charging material 21 to said tube.

It is to be observed that the solid portion of gate 37 or solid portion of upper plate 34 are effective to obtain a constant seal with respect to the vacuum in tube 28 and the body of the charging material, but that the gate, swinging laterally with respect to said tube, does not have to overcome differential pressures in order to move from one position to the other. The charging material is obtained from the body thereof below its surface and accordingly carries no surface contamination into the lamp.

Since the various details of construction, as well as the precise relation and functioning of parts are subject to variation and change without departing from the inventive concept or scope of the invention, it is intended that all matter contained in the specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

We claim:

1. A fluid-charging apparatus comprising a body portion providing a reservoir and having a charge-delivering outlet through the bottom of

said reservoir, a charge-delivering means in said reservoir above said outlet and movable horizontally across said outlet, said means having a measuring orifice for delivery of a measured portion of fluid contents of said reservoir to said outlet, and vertically movable cam within the reservoir in direct operating contact with said charge-delivering means.

2. A fluid charging apparatus comprising a body portion providing a reservoir for a fluid and having a charge-delivering outlet, and valve means for obtaining egress of a measured portion of said fluid from a part thereof below the fluid surface, said valve means being situated below said fluid surface and having a horizontal swinging movement in a plane substantially parallel to the bottom of said reservoir and to said fluid surface, and operating means for said valve means, said operating means having a restricted vertical path of sliding and extending in part through said valve means, all moving parts being confined to the region within and above the reservoir.

3. A fluid charging apparatus comprising a body portion providing a reservoir for a fluid and having a charge-delivering outlet, a valve structure providing a pivoted valve means having a measuring orifice and said valve structure having means for admitting fluid to said orifice at both the top and bottom thereof and having a part of said valve structure closing the top of said orifice while discharging the fluid therein to the charge-delivering outlet, and operating means for swinging said pivoted valve means, said operating means providing a pivot slidable with respect to the valve means and also acting as a stop for said operating means.

4. A fluid-charging apparatus comprising a body portion providing a reservoir for a fluid and having a charge-delivering outlet tube subject to evacuation, said body portion and tube providing a bleeder passage for equalizing pressure condition above the fluid in the reservoir to that of the tube, said bleeder passage preventing contamination reaching the tube to enter above the fluid level in the reservoir.

5. A fluid-charging apparatus comprising a body portion providing a reservoir for a fluid, a delivery tube in the bottom of said reservoir, a valve structure within the reservoir and carried upon the upper end of said tube below the fluid level in the reservoir, said valve structure including a movable gate, and reciprocal means for operating said gate comprising a yoke in said body portion above said gate and having cam means in displacing engagement with said gate, said yoke also having means thereon for preventing rotation thereof and for limiting reciprocation thereof.

6. A fluid-charging apparatus comprising a body portion providing a reservoir for a fluid, a delivery tube in the bottom of said reservoir, a valve structure within the reservoir and carried upon the upper end of said tube, said valve structure comprising parallel plates and an interposed horizontally swinging gate, said plates having aligned openings therein and said gate having an orifice adapted to register alternately with said openings and with said delivery tube.

7. A fluid-charging apparatus comprising a body portion providing a reservoir for a fluid, a delivery tube in the bottom of said reservoir, a valve structure within the reservoir and carried upon the upper end of said tube, said valve structure comprising parallel plates and an interposed

horizontally swinging gate, said plates having alined openings therein and said gate having an orifice adapted to register alternately with said openings and with said delivery tube, a vertically movable means having a cam slot for swinging said gate from one position to the other.

8. A fluid-charging apparatus comprising a body portion providing a reservoir for a fluid, a delivery tube in the bottom of said reservoir, a valve structure within the reservoir and carried upon the upper end of said tube, said valve structure comprising parallel plates and an interposed horizontally swinging gate, said plates

having alined openings therein and said gate having an orifice adapted to register alternately with said openings and with said delivery tube, and operating means for said gate comprising a yoke parallel thereto and having depending rods and cam bar parallel to each other and passing through the valve structure, one of said rods constituting a hinge for the gate and said cam bar having a cam slot for swinging said gate on its hinge from one position to the other.
